UNITED STATES PATENT OFFICE.

ALBERT G. MILLER, OF PHILADELPHIA, PENNSYLVANIA, ASSIGNOR TO LANKENAU HOSPITAL, OF PHILADELPHIA, PENNSYLVANIA, A CORPORATION OF PENNSYLVANIA.

SHIELD FOR ELECTRICAL APPARATUS.

Application filed May 22, 1920. Serial No. 383,388.

To all whom it may concern:

Be it known that I, ALBERT G. MILLER, a citizen of the United States, residing in Philadelphia, Pennsylvania, have invented 5 Shields for Electrical Apparatus, of which the following is a specification.

One object of this invention is to provide a relatively simple, substantial and convenient form of shield for use in connection 10 with high tension electrical apparatus and more particularly X-ray apparatus, for preventing accidental contact with the terminals of current carrying conductors associated therewith; the invention especially 15 contemplating the provision of an insulating protective casing made in separably connected parts designed to permit free access to the enclosed apparatus when this is desirable or necessary.

Another object of my invention is to provide a durable form of protective insulating casing consisting of adjustably connected sections supported to permit of their convenient separation, together with novel 25 means for insuring the assembly and retention of said sections in their normal protective positions.

These objects and other advantageous ends I attain as hereinafter set forth, reference 30 being had to the accompanying drawings, in which,

Figs. 1 and 2 are respectively a side elevation and a plan of a shield or casing constructed in accordance with my invention; 35 Fig. 3 is a horizontal section on the line 3—3, Fig. 1;

Fig. 4 is a vertical section on the line 4—4, Fig. 1; and

Fig. 5 is a perspective view of one of the 40 sections of the protective casing.

In the above drawings 1 represents a portion of the stand or platform carrying an X-ray tube with its associated apparatus which in the present instance includes terminals 2 and 3 connected to high tension current conductors (not shown). For mechanically protecting the tube and especially for preventing accidental contact with these terminals or with the conductors adjacent thereto, I provide an elongated casing made in two independently supported sections of relatively light insulating material as hereafter described. For supporting this casing I mount on the supporting structure or platform 1 a pair of parallel blocks 4, and pivot 55

to each of them a pair of lugs 5 projecting downwardly from opposite sides of a flat plate 6 of insulating material constituting the floor or bottom of one of the sections of my shield. 60

Each of said sections consists of a plate 6 suitably cut out to approximately fit around the X-ray tube and supporting a side section 7 in the form of a sheet of insulating material so bent at its middle that its two 65 parts extend at an acute angle to each other. On the upper edge of each of these side sections is mounted a substantially triangular frame 8 of relatively heavier insulating material. 70

The two substantially triangular prismatic casing sections, each made up of the sections 6, 7 and 8, are designed to have their base portions in engagement and for the purpose of separably holding them together, 75 I mount on their adjacent upper portions some form of conveniently operative latch or holding device such as the trunk fastener illustrated. This consists of a plate 9 fastened to one of the side sections 7 having a 80 projecting lug 10 designed to be engaged by a U-shaped spring actuated hasp 11 carried by a plate 12 on the adjacent edge of the other side section. 85

For insuring that the vertical meeting edges of the two casing sections 6, 7 and 8 are in lateral as well as in vertical registry, I form one of them with a series of projecting portions 13 in the form of corrugations designed to fit into corresponding recesses in the other section and as shown in Fig. 5, make the meeting edges of the two sections respectively overlap each other to prevent their lateral displacement. 90

In order to permit the user of the device 95 to ascertain the condition or operation of the apparatus within the casing, I provide in each of the side members 7 a series of windows, in the present instance two in each side of each section. For this purpose I 100 form the necessary holes in the insulating material of which the side sections are formed and over these place sheets 14 of transparent material such as mica, retaining them in place by cover sheets 15 of relatively 105 thin insulating material. While the casing sections may be made of any suitable non-conducting substance, I have found vulcanized fibre in sheet form to satisfactorily fulfill the required conditions. 110

When it is desired to open the casing, the catches are swung back from the lugs 10 whereupon the two casing sections are permitted to swing apart on their pivot screws 5 16 from the horizontal positions shown in full lines in Fig. 1 to the vertical positions illustrated in dotted lines. This exposes the X-ray tube and its terminals, permitting any desired adjustments or alterations to be 10 made. When however the sections are swung from their depending parallel positions into their horizontally aligned positions, they completely surround the X-ray tube and while the floor or bottom sections 6 are cut 15 out to permit the passage of the necessary tube supporting structures, etc., it is noted that it is a practical impossibility for any one to accidentally touch the terminals 2 and 3 or to approach within a dangerous proximity of the tube.

It is to be noted that the supporting structures 4 and their coacting lugs or blocks 5 are so positioned relatively to the casing that the two sections of the latter tend to 20 swing apart under the action of gravity but are restrained from so doing by the catches 25 11. Such an arrangement naturally facilitates the opening of the casing and does not materially affect the convenience of bringing 30 its parts together into the positions shown in full lines in Fig. 1, preparatory to locking them in their closed positions by the swinging catches 11.

I claim:—

35 1. A casing for electrical apparatus made in two parts each of approximately triangular prismatic form; means for detachably holding said parts with their basal portions immediately adjacent to each other to define 40 an elongated container; with pivots for independently supporting said sections to permit of their separation in a vertical plane and by a downward movement.

45 2. The combination of a supporting structure having two pairs of lugs; a casing made in two separable parts each having pivotal connection with one pair of the lugs and means for normally holding said sections together to form a protective shield for electrical apparatus.

50 3. The combination of a casing of insulating material made in two separable sections

having registering openings constituting an aperture; pivotal supporting means engaging the lower portions of said sections to 55 permit them swinging down and apart; and means for detachably connecting the sections in position to form a protective shield.

4. The combination in a protective casing for electrical apparatus of two separable 60 sections each consisting of a top frame member, a bottom member, and side portions rigidly connecting said members; means for pivotally supporting said sections independently of each other to permit of their swing 65 ing apart; and means for normally holding the sections together to define a protective casing.

5. The combination in a protective casing for electrical apparatus of two separable 70 sections; means for independently pivotally mounting said separable sections for motion in a common plane; means for laterally and vertically aligning said sections; and means for normally retaining the sections in their 75 closed positions to define a protective shield.

6. The combination of a casing of insulating material made in two sections having independent pivotal mountings, whereby the sections may swing toward and away from each other, said sections also having complementary co-acting side edges formed to align the sections vertically as well as laterally.

7. The combination in a protective casing for electrical apparatus of two separable 85 sections; pivotal supporting means for said sections positioned to cause them to separate and swing down and apart under the action 90 of gravity; with catches for normally holding the two sides of the sections together in the form of a protective shield.

8. In a protective casing for X-ray apparatus, the combination with a pair of housings having open top and end portions, of means for pivotally mounting said sections in such manner that the open end portions thereof are contiguous, forming a chamber open at the top, the pivotal mountings further being such that said sections tend to separate under the action of gravity, and means for securing the sections in their contiguous positions.

ALBERT G. MILLER.
